UNITED STATES PATENT OFFICE.

ARTHUR CONNOR, OF CHICAGO, ILLINOIS.

PLUG FOR ICE AND HOT WATER BAGS.

Application filed March 6, 1922. Serial No. 541,530.

To all whom it may concern:

Be it known that I, ARTHUR CONNOR, a citizen of the United States, and a resident of Chicago, in the county of Cook and State 5 of Illinois, have invented a new and useful Improvement in Plugs for Ice and Hot Water Bags, of which the following is a full, clear, and exact description.

My invention relates to improvements in 10 plugs for ice and hot water bags, and it consists in the combinations, constructions and arrangements herein described and claimed.

An object of my invention is to provide 15 a device of the character described having a plug which may be quickly and with little effort operated to seal the mouth of an ice or hot water bag.

A further object of my invention is to 20 provide a device of the character described, in which means is provided for locking the plug in its sealed condition by the pressure exerted from the water within the bag.

A further object of my invention is to 25 provide a device of the character described, which may be quickly opened with very little physical effort.

A further object of my invention is to 30 provide a device of the character described, which is very durable and which may be cheaply manufactured.

Other objects and advantages will appear in the following specification, and the 35 novel features of the invention will be particularly pointed out in the appended claims.

My invention is illustrated in the accompanying drawings, forming part of this 40 application, in which

Fig. 1 is a sectional view along the line 45 1—1 of Fig. 2,

Fig. 2 is a top plan view of the device 50 as shown in Figure 1,

Fig. 3 is a sectional view along the line 55 3—3 of Fig. 1,

Fig. 4 is an end elevation of the plug, and

Fig. 5 is a partial sectional view showing 60 one of the small ducts used in locking the plug.

In carrying out my invention, I make use 65 of the ordinary type of ice or hot water bag 1 having a relatively large open neck 2. A plug 3 of hard vulcanized rubber is closely fitted into the opening of the neck 2 and is provided with an outwardly extending portion, as shown at 4 for preventing 70 the plug 3 from being pulled out of the

neck 2. I shall hereinafter refer to the plug 3 as the body portion of the plug sealing device.

The body portion 3 is provided with a 75 cavity 5 in the upper surface thereof having an arcuate bottom surface 6, as shown in Fig. 3. The cavity 5 extends to a point adjacent the lower surface 7 of the body 3 and an elongated slot 8 is provided 80 through the body portion 3 connecting the cavity 5 with the interior of the bag 1. A metal plate 9 is securely fixed to the upper surface of the body 3 and a resilient plug 10 of soft pliant rubber is hingedly mounted 85 at one end thereof upon the plate 9 by means of a metal plate 11 attached thereto and connected by a hinge 12. The hinge 12 is riveted or otherwise fixed to the plate 9.

Means for locking the plug 10 in a position to seal the cavity 5 is provided for in a spring clip 13 riveted at 14 to the plate 9 and arranged to overlap the edge of the cavity 5. The spring clip 13 is of spring steel and will give slightly as the plate 11 90 engages therewith to permit the plate 11 to pass below the clip 13 and be yieldably held thereby.

Means for reenforcing the plug 10 and for holding the plug in its normal operative shape 95 and resilient condition is provided in a bolt 15, which bolt is passed through the plate 11 down through the plug 10 and through an elongated washer 16 disposed in a depression 17 on the under arcuate surface of the plug 10. The ends of the bolt 15 are enlarged to prevent the movement of the plate 11 and the washer 16. A second bolt 18 is connected to the washer 16 through the plug 10 and the plate 11. The bolt 18, however, extends beyond the upper surface of the plate 11 and is provided with a mushroom knob 19, by means of which the plug may be withdrawn 100 from its engagement with the cavity 5 or forcefully pressed into the cavity 5. Means for preventing the escape of water from the bag 1 between the contacting walls of the plug 10 and the body portion 3 and for forcing the plug 10 toward the clip 13 is provided in a rib 20 on one wall of the cavity 5 and a shallow groove 21 in the plug 10 and which groove is arranged to register with the rib 20 when the plug is closed and the rib 22 provided on the body portion 3 at the opposite end of the cavity 5, there being 105 a shallow groove 23, which groove is adapted to register with the rib 22.

Means for automatically locking the plug 10 against its seat in the cavity 5 is provided in the following structure. The plug 10 has at its outward end a downwardly extending tongue 24. The tongue 24 is tapered in a manner shown in Fig. 4 of the drawing. A cavity 25 in the end wall of the cavity 5 is provided to register with and receive the tongue 24 when the plug 10 is properly seated in the cavity 5. The outer wall 26 of the cavity 25 has formed thereon a plurality of transversely extending teeth 27. A pair of ducts 28 is provided in the body portion 3 and serve as a passage for water from the bag 1 to the under surface of the tongue 24. This is most clearly shown in Fig. 5. It should be noted that the ducts 28 are relatively small in diameter at a point adjacent the tongue 24 and relatively large at the points adjacent the bottom 7 of the body portion 3.

From the foregoing description of the various parts of the device, the operation thereof may be readily understood. In filling the bag, it is necessary first to manually grip the knob 19 and pull upwardly thereupon. The plug 10 will be disengaged from its seat in the cavity 5 and its engagement with the spring 13. The bag is then filled with hot or ice water. In closing or sealing the bag, the body portion 3 is held in the position shown in Fig. 3 with the bag properly lying in a horizontal plane. The surplus air is then worked out through the passage 8 and the plug manually forced to the position shown in Fig. 1 by pressure brought to bear on the knob 19. At this time the clip 13 will be engaged by the plate 11, the tongue 24 will be snugly fitted in the cavity 25 and the ribs 20 and 22 will bear upon the plug 10 in their respective grooves 21 and 23.

The bag is now ready for use. Let us assume that extreme pressure is placed upon the bag 1, such as the weight of a patient thereupon, as might occur if the bag were placed under a patient's shoulder or the like. The pressure of the water on the inside of the bag will tend to push the plug 10 away from its seat in the cavity 5. However, because of the particular construction of my plug, pressure will also be exerted upon the under surface of the tongue 24 by water which would pass through the ducts 28 and contact the under surface. This pressure upon the under surface of the tongue 24 will tend to force the tongue 24 into close engagement with the teeth 26 on the wall of the cavity 25 and the tongue 24 will be held against movement in the cavity. The spring clip 13 will furthermore exert a downward pressure upon the plate 11 and materially aid in locking the plug 10 against movement. As the pressure of the water or the contents of the bag 1 or the plug 10 is increased, the pressure exerted

upon the under surface of the tongue 24 will be increased proportionally and the plug 10 will therefore remain in its sealed position in the cavity 5 until it is manually lifted out of engagement with the cavity 5 by means of the knob 19. An important advantage of the structure heretofore described is that the body portion 3 is relatively flat and therefore does not present irregular surfaces which might irritate the patient from contact therewith.

I claim:

1. A device of the character described comprising a non-resilient body portion adapted to be permanently fitted in the neck of a hot or ice water bag, said body portion having a passage longitudinally therethrough, a plug hingedly mounted on said body portion and adapted to fit into and seal the mouth of said passage, and means actuated by the pressure of the liquid within the bag for locking said plug against movement in the mouth of said passage when pressure is applied exteriorly to the bag.

2. A device of the character described comprising a non-resilient body portion adapted to be permanently fitted in the neck of a hot or ice water bag, said body portion having a passage longitudinally therethrough, a plug hingedly mounted on said body portion and adapted to fit into and seal the mouth of said passage, means actuated by the pressure of the liquid within the bag for locking said plug against movement in the mouth of said passage when pressure is applied exteriorly to the bag, and a spring clip mounted on said body portion and adapted to yieldably engage said plug when in the mouth of said passage to further lock said plug against movement.

3. A device of the character described comprising a non-resilient body portion adapted to be permanently fitted in the neck of a hot or ice water bag, said body portion having a passage longitudinally therethrough, a plug hingedly mounted on said body portion and adapted to fit into and seal the mouth of said passage, means actuated by the pressure of the liquid within the bag for locking said plug against movement in the mouth of said passage when pressure is applied exteriorly to the bag, said means comprising a tongue integral with said plug, said tongue adapted to closely fit a cavity in one wall of said passage, teeth formed on one wall of the cavity in said passage, and a small duct through said body portion communicating with the under surface of said tongue in said cavity and with the interior of said bag, and a spring clip mounted on said body portion and adapted to yieldably engage said plug when in the mouth of said passage to further lock said plug against movement.

4. A device of the character described

- comprising a non-resilient body portion adapted to be permanently fitted in the neck of a hot or ice water bag, said body portion having a passage longitudinally therethrough, a plug hingedly mounted on said body portion and adapted to fit into and seal the mouth of said passage, means actuated by the pressure of the liquid within the bag for locking said plug against movement in the mouth of said passage when pressure is applied exteriorly to the bag, said means comprising a tongue integral with said plug, said tongue adapted to closely fit a cavity in one wall of said passage, teeth formed on one wall of the cavity in said passage, and a small duct through said body portion communicating with the under surface of said tongue in said cavity and with the interior of said bag, a spring clip mounted on said body portion and adapted to yieldably engage said plug when in the mouth of said passage to further lock said plug against movement, and a knob disposed on the upper surface of said plug for manually inserting and withdrawing said plug.
5. In a device of the character described, a non-resilient body member adapted to be permanently fixed in the neck portion of a hot or ice water bag, said body member being provided with a passage longitudinally therethrough, a resilient plug hingedly mounted on said body member and adapted to closely fit and seal the mouth of said passage, the opposite walls of said passage being formed with inwardly extending ribs integral therewith and adapted to closely engage the adjacent walls of said resilient plug when said plug is inserted in the mouth of said passage, a tongue integral with said plug, said tongue adapted to closely fit a cavity in one wall of said passage, teeth formed in one wall of the cavity in said passage, and a plurality of small tapered ducts through said body portion, each communicating with the under surface of said tongue when in said cavity and with the interior of said bag.
6. A device of the character described comprising a substantially firm body portion adapted to be fitted in the neck of a hot or ice water bag, said body portion having a passage extending longitudinally therethrough, a plug hingedly mounted on said body portion and adapted to fit into and seal the mouth of said passage, and means actuated by the pressure of the liquid within the bag for locking said plug against movement in the mouth of said passage when pressure is applied exteriorly to the bag.

ARTHUR CONNOR.
